(57) **CLAIM**

The ornamental design for a dual arm can actuator, as shown and described.

DESCRIPTION

FIG. 1 is a perspective view of a dual arm can actuator showing our new design in the unlocked and closed position;

FIG. 2 is a right side elevational view thereof;

FIG. 3 is a top plan view thereof;

FIG. 4 is a front elevational view thereof;

FIG. 5 is a left side elevational view thereof;

FIG. 6 is a rear elevational view thereof; and,

FIG. 7 is a perspective view of the dual arm can actuator shown in FIG. 1 showing our new design in the locked and closed position.

The dotted-line showing in the drawings illustrates environmental matter and forms no part of the claimed design.
